DESIGN FOR A KNIFE

Frederick K. Formis, West Hartford, Conn.

Application June 16, 1945, Serial No. 120,154

Term of patent 7 years

(Cl. D22—3)

To all whom it may concern:

Be it known that I, Frederick K. Formis, a citizen of the United States, residing at West Hartford, in the county of Hartford and State of Connecticut, have invented a new, original, and ornamental Design for a Knife, of which the following is a specification, reference being had to the accompanying drawing, forming part thereof.

Fig. 1 is a side elevation of a knife showing my new design.

Figs. 2 and 3 are front and rear elevations, respectively, of the knife.

I claim:

The ornamental design for a knife, as shown.

FREDERICK K. FORMIS.
